UNITED STATES PATENT OFFICE.

DANIEL M. TODD, OF ELGIN, ILLINOIS, ASSIGNOR TO ELGIN STREET SWEEPER CO., A COPARTNERSHIP CONSISTING OF SAID DANIEL M. TODD, JAMES TODD, AND CHARLES A. WHITING, ALL OF ELGIN, ILLINOIS.

STREET-SWEEPER.

1,348,605.

Specification of Letters Patent.

Patented Aug. 3, 1920.

Application filed February 5, 1919. Serial No. 275,185.

To all whom it may concern:

Be it known that I, DANIEL M. TODD, a citizen of the United States, residing at Elgin, in the county of Kane and State of Illinois, have invented certain new and useful Improvements in Street-Sweepers, of which the following is a specification.

The present invention has to do with certain improvements in machines for sweeping 10 and cleaning streets and the like. More particularly the invention has to do with a machine of this type in which use is made of a rotary brush or sweeper which is caused to rotate in contact with the street surface as 15 the machine travels along the street.

Machines of this type have, of course, been developed in the past, but so far as I am aware they have always been subject more or less to the objection that the brush would not 20 fully and completely remove dirt and other material from the curb, so that it has always been necessary to clean up close to the curb as a special cleaning operation. This is largely because it is customary to set the rotary brush or sweeper at an angle to the 25 length of the machine, and, consequently, the bristles of the brush have not been able to get down close to the street surface at the curb in order to perform their cleaning function at this point.

The main object of the present invention is to provide a machine of this type in which the brush is so constructed and operated that the bristles can and will at all times be forced 35 into thorough cleaning engagement with the surface of the street clear up to the curb line, notwithstanding the fact that the axis of the brush lies at an angle to the length of the machine instead of at right angles thereto.

Another object of the invention is to provide 40 an improved type of suspension for the brush whereby it is possible to regulate in more or less accurate fashion the pressure which the brush exerts on the street surface, 45 while at the same time flexibly supporting the brush so that it will easily ride over irregularities in the surface of the street.

Other objects and uses of the invention will appear from a detailed description of 50 the same which consists in the features of construction and combinations of parts hereinafter described and claimed.

In the drawings:

Figure 1 shows a plan view of a street

sweeper embodying the features of the present invention;

Fig. 2 shows a side elevation of said machine;

Fig. 3 shows a back view of the sweeper itself and the adjacent suspending mechanisms;

Fig. 4 shows a fragmentary detail view taken on the line 4—4 of Fig. 3, looking in the direction of the arrows;

Fig. 5 shows a detail cross section through the driving hub by means of which power is transmitted to the jack shaft for transmission to the brush; the same permitting an oscillating or swinging movement on the part of the brush itself without interfering with the proper transmission of the power;

Fig. 6 is a section taken on the line 6—6 of Fig. 5, looking in the direction of the arrows;

Figs. 7 and 8 are detail views showing a simple form of hinged pin permitting the double oscillating movement of the sweeping brush;

Fig. 9 is a fragmentary front view of the central portion of the brush and frame in which it is mounted showing a simple arrangement for effecting a spring suspension at this point which is capable of easy attachment;

Fig. 10 shows a fragmentary plan view of the bracket used in conjunction with the arrangement of Fig. 9;

Fig. 11 shows a fragmentary plan view of the sweeping brush with the top portion of the cover cut away so as to show the manner in which the guard plate deflects the bristles inwardly away from the curb until they reach a point low enough down to permit them to be released with assurance that they will strike in against the lower edge of the curb;

Fig. 12 is a fragmentary vertical view corresponding to Fig. 11, showing the manner in which the end bristles come into perfect engagement with the pavement at the curb line; and

Fig. 13 is an end perspective view corresponding to Figs. 11 and 12.

The features of the present invention may be incorporated into many forms and arrangements of street-sweeper, but for purposes of convenience in illustration, I have shown them as being incorporated into a

self-propelled sweeper in which an internal combustion engine is used for driving the machine along the pavement, as well as rotating the sweeping brush. This, however, is done only by way of illustration and is not to be understood as a limitation upon the usefulness or adaptability of the features of invention in connection with other styles or kinds of machine.

19 Bearing the foregoing in mind, the street sweeper illustrated in the figures includes a chassis 16 having a pair of front wheels 17 and 18, and a single rear wheel 19. The front wheels serve both for steering purposes and as drivers, and the rear wheel serves simply as a supporting wheel for the rear end of the chassis. The driving engine 20 is located under a suitable hood 21. The operation of the engine and the steering functions are controlled from a driver's seat 22 adjacent to which is the steering wheel 23 and the proper control levers, etc., 24.

20 The sweeping brush and its casing are designated in their entirety by the numeral 25. They are conveniently located diagonally across the frame or chassis of the machine, and preferably under its rear portion. This brush may be of any suitable length as compared to the width of the machine, but ordinarily its end portions 26 and 27 will project beyond the sides of the frame so as to insure a thorough cleaning of the pavement in both directions.

25 The brush itself is of any suitable construction but conveniently provided with a central axle 28 on which are mounted the bristles 29. The axle is journaled in a rectangular frame 30 comprising suitable bars or plates practically encircling the entire 35 length and width of the brush. Said frame lies in a substantially horizontal position, but is so supported and journaled that it can swing up and down or sidewise in order to permit of the movements of the brush which 40 are necessary or desirable in order to insure a thorough cleaning of the pavement at all points. The suspension illustrated includes a pair of bars 31 and 32 pivoted to the frame of the chassis at the points 33 and 34 and 45 pivoted to the frame of the sweeper brush at the point 35 and 36. The upper pivotal connections 33 and 34 are such as to permit the bars 31 and 32 to swing laterally or crosswise of the machine, whereas the pivotal 50 connections 35 and 36 are such as to permit the brush frame to swing longitudinally with respect to the frame of the machine, while at the same time permitting the front portion of the brush frame to rise and fall. 55 Figs. 7 and 8 show in detail a simple type of hinge for the points 35 and 36, the construction of which will be readily understood in conjunction with an examination of Fig. 4. Each of these hinges 35 and 36 includes a pin 37 which is journaled in a suit-

able bearing on the frame of the brush in conjunction with a pair of pins 38 and 39 which take into the bifurcations 40 at the lower ends of the bars 31 and 32 respectively. Examination of Fig. 4 will show that the 70 bars 31 and 32 are so constructed as to prevent any fore and aft swinging by reason of the length of the pivotal connection 34.

75 A chain 41 has its upper end 42 connected to the frame of the machine, and its lower end 43 connected to the lower portion of the bar 32 so as to limit the swinging of the brush toward the right in Fig. 3. A spring 44 has its upper end connected to a chain 45 connected to the frame of the machine and 80 its lower end 46 connected to a yoke 47, which yoke, in turn, has its lower end rigidly connected to the brush frame. This spring 44 tends to draw the brush frame toward the right in Fig. 3 until limited by 85 the chain 41, and the construction is such as to permit the brush to swing toward the left against the tension of the spring.

90 The front end of the brush frame tends to fall so that the weight of the brush frame and brush will be carried by the brush itself resting upon the pavement. However, the spring 48 is shown in Fig. 9 whose function, when used, is to carry a portion of the 95 weight of the frame so as to correspondingly relieve the pressure exerted upon the pavement. The upper end of this spring is connected to a chain 49 any desired link of which will be hooked over a bifurcated bracket 50 on the chassis of the machine, 100 and by hooking into the proper link, the tension on the spring 48 can be adjusted to the point desired.

105 The brush is ordinarily driven by a portion of the power from the engine in a direction contrary to the natural direction of rotation as would be dictated by the travel of the machine. For example, in Fig. 2, with the machine traveling toward the left, the brush is driven so as to travel in a direction of the arrows on said figure. This driving of the brush may be effected in any convenient manner from the engine of the machine, but a simple arrangement is that which I will now describe. This includes a 110 jack shaft 51 journaled in the chassis of the machine at a point above the rear end of the brush frame, said jack shaft being driven by the propeller shaft 52 through the medium of beveled gears 53 and 54. A suitable clutch or control may be used in conjunction with the propeller shaft 52. Another jack shaft 55 is journaled on the rear portion of the brush frame being provided at one end with a sprocket 56 and at the 115 other end with a sprocket 57. A chain 58 extends from the sprocket 57 to a sprocket 59 on the end of the brush shaft 28. The yoke 47 which was previously mentioned as being rigidly connected to the brush frame 120 includes a pin 60 which is journaled in a suit-

carries at its upper end a housing or the like 60 within which is journaled a sleeve 61 by the use of ball bearings 62 and 63. A sprocket 64 on the protruding end of the 5 sleeve 61 drives the chain 65 which passes down and over the sprocket 56 and serves to drive the jack shaft 55. A feathered shaft 65 works in a driving manner in conjunction with the sleeve 61, said shaft 65 being 10 driven from the jack shaft 51 through the medium of universal joints 66. This arrangement is such that the jack shaft 55 will at all times be in driving communication with the jack shaft 51 through the medium 15 of the chain 65, notwithstanding the swinging of the roller brush frame back and forth in the natural operation of the machine.

In order that the operation of the machine may be better understood and appreciated, 20 reference may now be had to Figs. 11 and 12, in which the brush is shown in the relationship which it ordinarily bears to the curb. In these figures the surface of the pavement is designated by the numeral 67 and the curb is 25 designated by the numeral 68. Since the brush turns over in a direction contrary to its natural direction of rotation as dictated by the travel of the machine along the street, and since the brush lies at a considerable angle 30 to the direction of the curb line, it follows that as the end bristles come around them they tend first to strike against the top of the curb and would naturally do so in the natural and ordinary operation of the machine. 35 Thereafter as soon as the roller had turned through a sufficient angle, the bristles would snap away from the top of the curb. By the time they reach the pavement, they would come into contact with the pavement 40 at a point some distance removed from the lower edge of the curb, thereby leaving a considerable gap or space at the point where the curb and pavement has come together uncleaned and filled with dirt and refuse.

In order to overcome the foregoing natural tendency and in order to insure a thorough and complete contact of the bristles with the surfaces of the pavement clear up to the curb line, I have illustrated the expedient 45 which I will now describe. The same comprises a guard or baffle plate 69 firmly supported adjacent to and in contact with the upper end portion of the sweeping roller, said baffle plate or guard 69 lying substantially 50 parallel to the length of the machine and, therefore, substantially parallel to the direction of the curb itself. The lower edge 70 of this baffle plate extends down low enough to insure that the bristles will be carried to a 55 point below the upper edge 71 of the curb before they are released from the influence of the baffle plate, so that when so released they will snap out to their full natural extension and thus insure full contact with the 60 surfaces of the pavement up to the curb in the 65

manner which will be readily understood from an examination of Figs. 3, 11, 12, and 13. Ordinarily this baffle plate will extend upwardly substantially the full height of the sweeping roller, so that the bristles will 70 come into contact with it in an easy manner as they pass over the uppermost point of their travel. Thereafter as they move downwardly in the rotation of the roller, they will be forced inwardly and not allowed to 75 snap out until they reach the desired low elevation.

I claim:

1. In a street sweeper, the combination with a wheeled carriage, of means for driving the same along the pavement, a sweeping brush, a frame wherein said brush is journaled, means for suspending such frame from the carriage to permit oscillation of the frame lengthwise of the roller, a spring 80 tending to move the frame sidewise to carry the sweeping roller toward the curb, means for limiting such movement, and means for driving the roller for sweeping purposes in any lateral position of the frame with respect to the carriage, substantially as described. 85

2. In a street sweeper, the combination with a wheeled carriage, of a frame extending across said carriage, a sweeping brush journaled in said frame, means for suspending the frame from the carriage while permitting the frame to swing sidewise with respect to the carriage, flexible means tending 90 to move said frame to carry the brush toward the curb, and means for limiting such movement, and means for driving the brush for sweeping purposes when the frame stands in any position of sidewise swing, 95 substantially as described. 100

3. In a street sweeper, the combination with a wheeled carriage, of a sweeping brush extending across the carriage, suitable journals for said brush in which it rotates, means for supporting said journals from the carriage to permit the journals to move sidewise with respect to the carriage, flexible means tending to carry the journals sidewise to thereby move the end of the brush toward the curb, means for limiting such movement, 110 and means for driving the brush from the carriage in any lateral position of the brush with respect to the carriage, substantially as described. 115

4. In a street sweeper, the combination with a wheeled carriage and means for driving the same along a pavement, of a substantially rectangular brush frame lying in a substantially horizontal plane, a brush journaled in the same, an upstanding bracket secured to said frame, a jack shaft journaled in the lower portion of said bracket and lying substantially parallel to the brush axis, a driving connection between said jack shaft and the brush, a rotatable element journaled 120 125 130

in the upper portion of said bracket, a driving connection between the jack shaft and said element, another shaft in alignment with the rotatable element in the upper end of the bracket, a splined connection between said aligned shaft and rotatable element and suitable supports for the brush frame permitting said frame to swing axially with respect to the brush axis and permitting said frame 10 to swing about a horizontal axis parallel to the brush axis while preventing the brush frame from moving forwardly and backwardly, substantially as described.

5. In a street sweeper, the combination 15 with a wheeled carriage and means for driving the same along a pavement, of a substan-

tially rectangular brush frame lying in a substantially horizontal position, a brush journaled in the same, an upstanding bracket secured to the brush frame, a rotatable element 20 journaled in the upper end of said bracket, a shaft aligned with said rotatable element, a splined connection between said shaft and rotatable element, driving connections between the first mentioned shaft and the 25 brush and suitable mountings for the brush frame permitting said frame to swing sideways with respect to the carriage, while preventing the brush frame from moving forwardly and backwardly with respect to the 30 carriage, substantially as described.

DANIEL M. TODD.
